INVENTOR

Charles E. Langmaid

UNITED STATES PATENT OFFICE.

CHARLES E. LANGMAID, OF STONEHAM, MASSACHUSETTS.

SHINGLER'S BRACKET.

SPECIFICATION forming part of Letters Patent No. 230,425, dated July 27, 1880.

Application filed December 22, 1879.

To all whom it may concern:

Be it known that I, CHARLES E. LANGMAID, of Stoneham, in the county of Middlesex and State of Massachusetts, have invented new and useful Improvements in Shinglers' Brackets, of which the following is a specification.

The nature of my invention consists in combining with a shingle-gripping clamp a triangular frame which, when open, forms a bracket upon which a board may be placed to form a rest for the shingler and his appliances. The parts that form two sides of the bracket also serve as levers for closing the clamp onto the holding-shingle, while the third side consists of a toggle which, when straight, firmly braces the first-mentioned sides open, so as to constitute a bracket; but when this toggle is bent outwardly the other sides fold together and open the clamp, so as to release the device from the shingle.

In the drawings, Figure 1 is a perspective sketch of my invention. Fig. 2 is a vertical section of the same.

In the drawings, let A in dotted lines represent the shingles; H and H', the clamps which gripe the shingle A. (See Fig. 2.)

One jaw, H, of the clamp is attached to the

piece B, while the other jaw, H', is attached to the piece C. The pieces B and C are pivoted together at e, and held by the housing E. 30

D and D' are toggles, which are hinged at L and L', respectively, to the pieces B and C, and are hinged to each other by the hinge L''. K is a serrated metal piece that penetrates the shingle and assists in holding the bracket to 35 the roof.

To use my invention it is only necessary to bend the toggle D D' outwardly, as shown in Fig. 2. This will open the jaws H H', and then it may be slipped over and under the 40 shingle A, Fig. 2. Now, by straightening the toggle D D', as shown in Fig. 1, the jaws H H' firmly grasp the shingle, and the bracket will stay in place.

I claim—

In a shingle-bracket, the combination of the jaws H H' with the side pieces, B and C, and the toggle D D', substantially as described, and for the purpose set forth.

CHARLES E. LANGMAID.
